UNITED STATES PATENT OFFICE

IRVING FLORMAN, OF NEW YORK, N. Y.

DESIGN FOR A POCKET ATOMIZER

Application filed October 30, 1930. Serial No. 37,440. Term of patent 14 years.

To all whom it may concern:

Be it known that I, IRVING FLORMAN, a citizen of the United States, residing at New York, in the county of New York and State of New York, have invented a new, original, and ornamental Design for a Pocket Atomizer, of which the following is a specification, reference being had to the accompanying drawing, forming a part thereof.

Fig. 1 is a top view of my design.

Fig. 2 is a front view of the design.

The opposite side of the atomizer embodies the same design as the side shown in Fig. 2.

I claim:

The ornamental design for a pocket atomizer, as shown and described.

IRVING FLORMAN.
